GRASS SHEARS OR THE LIKE

David H. Keiser, Jr., 53 Park Road, Wyomissing Hills,
West Lawn, Pa.

Filed May 17, 1965, Ser. No. 85,303

Term of patent 14 years

(Cl. D22—4)

FIG. 2.

FIG. 3.

FIG. 4.

FIG. 5.

FIG. 6.

FIG. 7.

FIGURE 1 is a side elevational view of a pair of grass shears, showing my new design;

FIG. 2 is a top plan view of a combination cutting blade and operating lever which forms part of the grass shears shown in FIG. 1;

FIG. 3 is a front elevational view of FIG. 2;

FIG. 4 is a bottom plan view of FIG. 2;

FIG. 5 is a rear elevational view of FIG. 2;

FIG. 6 is an end elevational view, as seen from the right of FIG. 2; and

FIG. 7 is an end elevational view, as seen from the left of FIG. 2.

The dominant features of my design reside in the full line portions of the drawings and consist essentially in the cutting blade and operating lever as shown in detail in FIGS. 2-7 inclusive.

This is a continuation-in-part of design application Serial No. 80,612 filed June 29, 1964.

I claim:

The ornamental design for grass shears or the like, substantially as shown and described.
